J. F. Schüffenecker,

Brick Mold.

N°27,652

Patented Mar. 27, 1860.

Fig. 3.

UNITED STATES PATENT OFFICE.

J. F. SCHUFFENECKER, OF KEOKUK, IOWA.

BRICK-MOLD.

Specification of Letters Patent No. 27,652, dated March 27, 1860.

To all whom it may concern:

Be it known that I, J. F. SCHUFFENECKER, of Keokuk, in the county of Lee and State of Iowa, have invented a new and useful 5 Improvement in Brick-Molds with Movable Bottoms; and I do hereby declare that the following is a full, clear, and exact description of the construction and operation of the same, reference being had to the annexed 10 drawings, making a part of this specification, in which—

Figure 1, is a top view (or upper surface). Fig. 2, is a front view. Fig. 3, is another front view. Fig. 4, is an end view.

15 *Description of the front views Figs. 2, 3.*—A, are the bottoms, B, are the molds; C, the handle of the molds; D, is a lever, the lower end of it has a slot; E an axle on which the lever D is acting; F, a rod which moves in a straight line and is supported by two guides G, H is a wrist which connects the rod F, to the lever D, the slot in the lever is necessary in order to permit the rod F to move in a straight line. J, J° 20 is a part of the rod F, and represents two wedges which stand in an inclined position; K, a vertical slide with its upper part fastened to the bottoms; L, a guide which holds the slide in a vertical position; I, I° cogs and parts of the slide K. These cogs are 25 partially in contact with the wedges J, J°, as shown in Figs. 2 and 3.

30 *Description of the end view Fig. 4.*—D, is a cross part of the lever D, the bottoms are pressed against the mold by that lever through the connections of the rod F, wedge J, cog I, and slide K, as shown Fig. 2. The 35 moving of the bottoms is effected by the indirect movement of the lever D, rod F,

wedge J°, cog I° and slide K, as shown 40 Fig. 3. M is a plate fastened to the handle of the molds, N, is a spindle fastened to the said plate. O is a lock bar which secures the bottoms to the molds and thus prevents the sand and mortar from settling between 45 the bottoms and molds if it stands in a vertical position, as shown partially in the end view Fig. 4.

The object of this improvement is, to effect a more easy delivery of the bricks upon the 50 drying floor.

I will now describe the operation of the molds.

The bottoms are moved by the two motions half right and half left as shown Figs. 2 55 and 3. Place the molds upon the drying floor without shaking, reverse the lock bar as shown by dotted line Fig. 4, push the cross parts of the levers D, toward the ends of the molds as shown Fig. 3, take hold of 60 the handle of the molds and deliver the bricks, put your mold upon the drying floor at the rear end of the bricks, reverse the lever D as shown Fig. 2, and secure it by the lock bar O as shown partially Fig. 4, 65 and the mold is ready to be sanded and filled.

I make no claim to the construction of the molds, but

What I do claim as my invention, and desire to secure by Letters Patent is— 70

Operating the bottoms of the molds by means of the lever D, rod F, wedges J, J°, cogs I, I°, slide K, and lock bar O, in the manner and for the purpose specified.

J. F. SCHUFFENECKER.
